DETACHABLE-HOOD GARMENT

William Lipson, Brookline, Mass.

Application February 18, 1935, Serial No. 7,090

3 Claims. (Cl. 2—84)

The present invention relates to hooded garments, particularly such as are used by aviators, and its chief object is to provide a new and improved garment of the above-described character 5 that shall be provided with a novel, detachable, reversible hood, and that may, if desired, serve as a pocket when detached.

Other and further objects will be explained hereinafter and will be particularly pointed out in 10 the appended claims.

The invention will now be more fully explained in connection with the accompanying drawings, in which Fig. 1 is a front elevation of an aviator's coat, showing the detachable hood in place, positioned inside the coat; Fig. 2 is a perspective of the hood, shown detached, but upon a larger scale than in Fig. 1; Fig. 3 is a section taken upon the line 3—3 of Fig. 1, looking in the direction of the arrows; Fig. 4 is an elevation similar to Fig. 1, 15 showing the hood swung outside the coat, ready for use; Fig. 5 is a fragmentary section taken upon the line 5—5 of Fig. 1, looking in the direction of the arrows, the parts being shown detached, and the scale being larger than in Fig. 2; Fig. 6 is a side elevation corresponding to Fig. 4, with 20 the collar of the coat raised; Fig. 7 is a section similar to Fig. 3, the hood being shown reversed with respect to the showing of Fig. 3, and showing also, in dotted lines, the hood swung outside of 25 the coat; Fig. 8 is a section similar to Fig. 5 of a modification; Fig. 9 is a section similar to Figs. 3 and 7, but with the hood serving as an inside pocket; Fig. 10 is a fragmentary view inside the coat, near the collar thereof, of a further modification, the hood being shown detached, the scale 30 being as in Figs. 5 and 8; and Fig. 11 is a section taken upon the line 11—11 of Fig. 10, looking in the direction of the arrows.

A hood 2 is shown detachably connected to the 40 inside of a coat 4 at the neck portion 6. As shown in Figs. 1 to 5, the inside of the neck portion 6 may be provided with snap sockets 8 into which are adapted to snap buttons 10 upon the lower margin 12 of the hood 2. When the buttons 10 are snapped into the sockets 8, the hood may 45 occupy the normal position shown in Figs. 4 and 6, swung outside of the coat, ready for use. The hood may, however, be swung inside the coat, as shown in Figs. 1, 3 and 5, when it is desired not to 50 use the hood, the hood then resting inside the coat, against the wearer's back, when the coat is being worn.

When the hood is thus inside the coat, as shown 55 in Figs. 1 and 3, there is a bend 14 in the hood, near the said lower margin 12. The hood is, how-

ever, reversible. When so reversed, it may occupy the position illustrated in Fig. 7, in which the hood is disposed inside the coat without any such bend as shown at 14. This may be regarded as the normal position of the hood in this reverse condition of the hood. A bend 16 will, however, be produced if the hood be swung outside the coat, as shown in Fig. 7 by dotted lines. The reversibility of the hood is rendered possible by suitable shaping of the hood; as by providing a 10 seam 18, as shown.

The snap sockets 8 may, of course, be provided in the hood and the snap buttons 12 upon the coat; or buttonholes 20 may be provided upon either of these members, and buttons 22 on the other, as shown in Fig. 8; or a zipper mechanism 24 may be provided upon one of these members and a cooperating zipper mechanism 26 on the other, as illustrated in Fig. 10, or other detachable securing means, such as hooks and eyes, 20 may be provided, all within the spirit and scope of the invention.

Because of the fact that the hood is secured to the inside of the neck portion 6, it may be swung inside the coat or outside the coat without interference by the coat collar, which is shown raised in Fig. 6. If the hood were fastened outside of the coat, the collar would interfere with this swinging movement of the hood; more than that, the fit would not be snug, but the hood would 30 be open and tend to fall down against the back of the coat when in use and, as a result of such construction, the wind and snow would enter between the coat and the wearer, near the neck. All these difficulties are overcome by the present 35 invention.

Among other advantages of the present invention, when the hood is swung inside the coat, as shown in Figs. 1 and 3, and in full lines in Fig. 7, a double back is provided by the hood and the 40 back of the coat, which double back furnishes extra warmth for the back of the wearer. On the other hand, if desired, the coat may be used as an ordinary coat, merely by detaching the hood.

By "ordinary coat" is meant a coat of the illustrated type, with sleeves and a collar permanently attached to the neck portion 6, and folded back over the outside of the coat at the back, the sides and the front of the coat. Coats of this type are 50 frequently employed, for example, by aviators and motorists. With the hood in place, as shown in Fig. 4, for example, with the lower margin 12 of the hood detachably fastened to the inside of the coat at the said back, the sides and the front 55

of the coat at the neck portion 6, a mere closing of the coat upon the body of the wearer will automatically result in a closing of the back, sides and front portions of the hood against the 5 sides of the wearer's face; and when the coat is buttoned at the top, the hood, by reason of its before-mentioned shape, and the fact that the said lower margin 12 extends along the back, the sides and the front portions of the hood, and 10 the fact that the snap buttons 10 upon the two front portions of the said lower margin 12 of the hood cooperate with the snap sockets 8 upon the front portion of the coat, will remain closed tight, with the back of the hood against the back of 15 the wearer's head, the sides of the hood tight against the wearer's cheeks, and the front of the lower marginal portion of the hood against the front of the wearer's neck, thus preventing the entry of wind and snow. By reason of the fact 20 that the hood is detachable, different hoods may be supplied by the dealer with the same coat, to fit snugly against the heads of different wearers, and a new hood may readily be obtained when lost. And by reason of the reversibility of the 25 hood, it has a double life, as it may be reversed when faded or worn.

In some cases, the hood, when not in use, may be attached to a side portion 28 of the coat 4, as 30 by means of buttons and button-holes 30, illustrated in Fig. 9, so as to provide an additional inside pocket.

Modifications will occur to persons skilled in the art, and all such are considered to fall within the spirit and scope of the invention, as defined in the appended claims.

What is claimed is:

1. A coat provided with sleeves, a neck portion and a collar permanently attached to the neck portion and folded back over the outside of the 40 coat at the back, the sides and the front of the coat, a hood separably attached to the coat, said hood having a back, sides and front portions and having a lower margin at the said back, sides and front portions, fastening means on the inside of the coat near the neck portion and including the front portion of the coat, and cooperating fastening means at the said lower margin of the hood and including the said front portions of the said lower margin of the hood, the fastening 45 means and the cooperating fastening means be-

ing adapted to cooperate to detachably connect the said lower margin of the hood to the inside of the coat at the neck portion of the coat including the front portion of the said neck portion of the coat.

2. A coat provided with sleeves, a neck portion and a collar permanently attached to the neck portion and folded back over the outside of the coat at the back, the sides and the front of the coat, a hood separably attached to the coat, said 10 hood having a back, sides and front portions and having a lower margin at the said back, sides and front portions, snap members on the inside of the coat near the neck portion and including the front portion of the coat, and cooperating 15 snap members at the said lower margin of the hood and including the said front portions of the said lower margin of the hood, the snap members and the cooperating snap members being adapted to cooperate to detachably connect the said 20 lower margin of the hood to the inside of the coat at the neck portion of the coat including the front portion of the said neck portion of the coat.

3. A coat provided with sleeves, a neck portion and a collar permanently attached to the neck 25 portion and folded back over the outside of the coat at the back, the sides and the front of the coat, a hood separably attached to the coat, said hood having a back, sides and front portions and having a lower margin at the said back, sides and 30 front portions, fastening means on the inside of the coat near the neck portion and including the front portion of the coat, and cooperating fastening means at the said lower margin of the hood and including the said front portions of the said 35 lower margin of the hood, the fastening means and the cooperating fastening means being adapted to cooperate to detachably connect the said lower margin of the hood to the inside of the coat at the neck portion of the coat including the front portion of the said neck portion of the coat, and the hood being reversible, whereby the hood may be positioned normally inside of the coat, without bending the material of the hood, in one position of attachment of the hood to the 40 coat and to be positioned normally outside of the coat, without bending the material of the hood, in the reverse position of attachment of the hood to the coat.
